US00D604593S

(12) United States Design Patent
Seehoff et al.

(10) Patent No.: US D604,593 S
(45) Date of Patent:  Nov. 24, 2009

(54) RING HOLDER

(75) Inventors: Gary Stanley Seehoff, Encino, CA (US); Christopher Anzalone, Foothill Ranch, CA (US)

(73) Assignee: Evriholder Products LLC, Anaheim, CA (US)

() Term: 14 Years

(21) Appl. No.: 29/330,239

(22) Filed: Dec. 31, 2008

(51) LOC (9) Cl. 08-05

(52) U.S. Cl. D8/367

(58) Field of Classification Search D6/323; D8/363, 367, 371, 373; 248/301-304, 339
See application file for complete search history.
